UNITED STATES PATENT OFFICE.

BERNARD M. DRAWE, OF SANDUSKY, OHIO, ASSIGNOR OF ONE-THIRD TO
ROBERT WEIGEL, OF SANDUSKY, OHIO.

WATER-CLOSET.

No. 823,770.

Specification of Letters Patent.

Patented June 19, 1906.

Application filed April 4, 1905. Serial No. 253,763.

To all whom it may concern:

Be it known that I, BERNARD M. DRAWE, a citizen of the United States, residing at Sandusky, in the county of Erie and State of Ohio, have invented a certain new and useful Improvement in Water-Closets, of which the following is a full, clear, and exact description, reference being had to the accompanying drawings.

10 The object of this invention is to provide an efficient water-closet which may be operated directly by the pressure in the main.

The invention comprises mechanism whereby a simple operation of a lever or other suitable release initiates means which automatically open a gate, allowing the water to siphon the bowl. An auxiliary jet is provided at the base of the bowl to augment the siphoning action. These and other features are 20 comprised within the invention, which may be most conveniently summarized as consisting of the construction and combination of parts hereinafter more fully explained, and definitely set out in the claims.

25 In the drawings, Figure 1 is a vertical longitudinal section through the closet. Fig. 2 is a side elevation thereof, partly broken away. Fig. 3 is a side elevation on the side opposite Fig. 2. Fig. 4 is a vertical section 30 on the line 4 4 of Fig. 3 looking to the right. Fig. 5 is a horizontal section substantially on the line 5 5 of Fig. 1. Fig. 6 is a horizontal section on the line 6 6 of Fig. 1, showing also the base of the structure. Fig. 7 is a detail 35 in horizontal section on the line 7 7 of Fig. 4.

The same letters of reference designate the same part in each figure.

As shown in the drawings, the bowl, base, and the various chambers hereinafter described may be made of one piece—as cast-iron or porcelain, for example—while the gate mechanism is a self-contained structure removable therefrom. The stationary part A includes the base-plate a, the sides a', the front a'', the bowl a'', having a rolled-over upper edge a'', which supports the seat. (Not shown.) At the base of the bowl a passage-way a'' leads upward beneath the wall a'' of the bowl, over a diaphragm a'', and then 45 downward at a'' between the diaphragm a'' and the front wall a'' into the passage-way a''. The exit from the passage-way a'' leads beyond the gate b and down through the pas-

sage-way b', which, as stated, is carried by the separate gate mechanism B.

55 In normal position the exit is closed by the curved gate b, which engages at its lower end with the base-plate b'' and near its upper end with the member b'', which forms a tight connection with the lower portion of the bowl. At its upper end the gate is rigidly connected with a bucket b'', this whole gate structure being pivoted at b'' on the upper side of the wall b'' of the discharge passage-way.

60 On one side of the structure a tubular passage-way C leads from the bend a'' to a pocket a'' directly over the bucket, while on the opposite side a passage-way D leads from the chamber a'' (which has valved communication with the main, as hereinafter explained) 70 to the pocket a'' at the base of the bowl.

65 The purpose of the particular features of construction above described can be best understood from an explanation of the flushing operation. In normal position the water in 75 the bowl stands on a level with the meeting-point of the diaphragms a'' and a''. When it is desired to flush the bowl, water is admitted by the operation of the valve H, as hereinafter explained, into the chamber a'', from 80 whence it flows into the opening a'' and thence into the passage-way a'' in the rolled-over edge a'' at the upper end of the bowl. The water continues to flow from this source until the passage-way a'' is entirely filled, as 85 well as the space between the diaphragm a'' and the front wall a'', the water rising high enough in these places to enter the upper end of the tubular passage-way C. Thereupon water flows through this pipe C into the 90 pocket a'' and thence into the bucket b'' until such bucket is more or less nearly full, whereupon the weight of the water in the bucket causes it to swing downward, raising the gate b and releasing the water in the bowl and the 95 passage-ways a'' and a'', which thus goes into the discharge-opening with a rush, effectively siphoning the bowl. During the siphoning water from the chamber a'' passes by the pipe D into the pocket a'' at the base of the 100 bowl and is discharged diagonally upward through an inclined opening a'', and thus flows up along the diaphragm a'', effectively boosting or augmenting the flushing operation.

105 At the beginning of the flushing operation

the bucket b^4 is swung down into its lowermost position, thus causing a pin b^7 on the valve b^8 to impinge against the wall b^9 , opening this valve and releasing the water therein, which 5 passes through the opening b^{10} into the discharge passage-way. The valve-opening b^8 is made of such size that the desired interval of time elapses after the bucket has swung down before it becomes sufficiently empty to 10 return. After the bucket has emptied itself the gate b swings back by gravity into the normal position, thus closing the exit. A hole b^{11} is made through the plate b^8 of the bucket, so that water will remain on the front side of 15 the bucket and retard its downward operation.

It now remains to describe the manually-operated mechanism for turning on the water and the automatic arrangement which results in its being shut off at the proper time. 20 The operation is initiated in any manner desired. As shown in the drawings, a hand-lever E is provided for the purpose. This lever is pivoted to the frame on a rock-shaft which 25 carries an internal arm E , extending through a vertical rod F . Thus when the hand-lever is raised this rod is raised. The rod is guided in the chamber a^{14} and at its lower end passes through a lever G , which is connected with 30 the stem h on the main valve H . The bonnet H' , surrounding this valve, is connected with the water-main. When the rod F is raised, the disk f' on the lower end thereof engages the lever G and swings it to lower the 35 valve H , thus opening communication with the water-main, whereby water is admitted to the chamber a^{14} . In the above-described movement the disk f' on the rod F engages and passes above the spring-finger j^4 , where- 40 by the valve is held open, so that the operator's hand may be removed from the lever E as soon as it is raised. The valve H being held open, water is admitted into the chamber a^{14} , and from thence some of it passes out 45 through the opening a^{18} into the outside pipe D , furnishing the boosting-jet through the opening a^{16} into the base of the bowl, as hereinbefore explained. The raising of the rod F causes the diaphragm f , carried thereby, to 50 pass above the opening a^{10} , leading to the annular passage-way a^{11} , wherefore water is admitted to such passage-way and flows from thence into the bowl, and after it has reached the proper height in the bowl and in the exit 55 passage-ways therefrom it flows back through the outside pipe C , as hereinbefore explained, into the bucket. When the filled bucket tips, it engages a rod j' , depending from an arm j^2 , rigid on a rock-shaft j^3 , which carries the 60 spring-arm j^4 . This movement rocks the shaft, so that the spring-arm j^4 releases the disk f' ; but just preceding such release a second arm j^5 , carried by the rock-shaft, engages beneath a projection g on the lever G and 65 holds it elevated. The flow of water thus

continues until the bucket swings back into normal position. In this movement the rod j' is again engaged to swing the rock-shaft to cause the fingers j^4 and j^5 to return to normal position. In this movement the finger j^4 70 swings idly above the disk f' , (which when released dropped down below the path of the finger,) and the finger j^5 releases the projection g , thus allowing the valve to close, which it does gradually, the disk f on the rod F preventing too sudden movement. The rock-shaft j^3 is carried by a suitable stuffing-box or similar member j^6 , while to prevent the leakage of sewer-gas around such rod the rod carries a cup j^7 , which catches water leaking 75 around the rod, and thus makes a water seal. A removable plate K is secured to the side of the casing opposite the elbow of the admission-pipe. The removal of this elbow and this plate allows sufficient access to the interior for the purpose of installing and adjusting 80 the parts.

It will be seen that the operating mechanism for the gate is entirely on the sewer side thereof and that there is no mechanism in 90 the passage-way between the bowl and the gate, so that when the gate is open there is an unobstructed conduit to the sewer. This is an important point, as it prevents the collection of waste matter on the forward side of 95 the gate. The water seal in the cup j^7 prevents any sewer-gas from passing up into the chamber a^{14} , while any gas which passes into the chamber a^{13} is prevented by the water in the bend of the pipe C from entering the 100 bowl. The water normally standing in the bowl above the lower end of the wall a^{10} forms the usual seal at this point.

The positive gate across the discharge-pipe besides being useful in most installations in 105 barring the sewer-gas from the bowl is especially advantageous when the fixture is used on shipboard, where the gate prevents water swashing up the discharge-pipe from backing into the bowl and spattering therein, as frequently happens with many fixtures.

I claim—

1. In a water-closet, the combination of a bowl, a removable gate mechanism for closing the discharge passage-way therefrom, 115 said gate mechanism including a portion of the discharge-conduit, a member adapted to move across the same, and a bucket connected with said member for moving it.

2. In a water-closet, the combination of a 120 bowl, a passage-way therefrom, and a removable gate mechanism for closing said passage-way including a base-plate, a casing carried thereby and forming a portion of the discharge passage-way, a bucket pivoted on the 125 upper side of the casing, and a gate connected with the bucket and movable through a slot in the casing.

3. In a water-closet, the combination of a bowl, a passage-way therefrom, pivoted gate 130

- mechanism for closing said passage-way including a plate adapted to project downward through a slot in the upper wall of the discharge passage-way, and a bucket rigidly connected with such plate.
4. In a water-closet, the combination of a bowl, a passage-way therefrom, a gate for closing said passage-way, said gate being arc-shaped and pivoted at its center of curvature, a bucket connected with the gate beyond the pivot thereof, and means for directing water into the bucket.
5. In a water-closet, the combination of a bowl, a passage-way therefrom, water-operated mechanism for controlling the passage-way, and a pipe leading to said mechanism from a point in the discharge passage-way.
6. In a water-closet, the combination of a bowl, a passage-way therefrom, a gate for the passage-way, a bucket for operating the gate, and a pipe leading from a point in the discharge passage-way to said bucket, said pipe bending downward intermediately of such points.
7. In a water-closet, the combination of a bowl, a passage-way therefrom, a gate for the passage-way, a bucket for operating the gate and a pipe leading from a point in the discharge passage-way to said bucket, said pipe starting at a point in the discharge-pipe above the normal water-level.
8. In a water-closet, the combination of a bowl, a passage-way from the base thereof leading upward and then downward and backward, gate mechanism adapted to be operated by water for controlling the passage-way, a pipe leading from a comparatively high point in the passage-way to such gate mechanism, and valve mechanism for controlling the admission of water to the bowl.
9. In a water-closet, the combination of a bowl, a passage-way therefrom, gate mechanism

adapted to be operated by water for controlling the passage-way, a pipe leading from the passage-way to such gate mechanism, valve mechanism for controlling the admission of water to the bowl, means for manually opening the valve, means for thereafter holding it open, and means operated by the gate mechanism for thereafter allowing the valve to close.

10. In a water-closet the combination of a bowl, a passage-way therefrom, a gate for the passage-way, and means for concurrently operating the gate and admitting a boosting-jet to the base of the bowl.

11. The combination of a bowl, an exit passage-way therefrom, a gate for closing such passage-way, water-operated means for, moving said gate, a valve for admitting water to such means, mechanism for opening said valve, and mechanism for retarding the closing thereof.

12. The combination of a bowl, a passage-way therefrom, a gate for closing the passage-way, a bucket for operating the gate, a valve for admitting water to the bucket, means for opening said valve to initiate the admission of water, mechanism for retarding the closing of the valve, such mechanism being operated by the moving of the bucket to allow the valve to close.

13. The combination of a bowl, a gate therefor, water-controlled means for opening the gate, a valve for admitting water to such means, and mechanism operated by such means for governing the closing of such valve.

In testimony whereof I hereunto affix my signature in the presence of two witnesses.

BERNARD M. DRAWE.
